UNITED STATES PATENT OFFICE.

WILMER STANLEY SNOW, OF OAK PARK, ILLINOIS, ASSIGNOR TO CROWN ELECTRICAL
MANUFACTURING COMPANY, OF ST. CHARLES, ILLINOIS, A CORPORATION OF
ILLINOIS.

DESIGN FOR A LIGHTING FIXTURE.

Application filed November 28, 1925. Serial No. 15,568. Term of patent 3½ years.

To all whom it may concern:

Be it known that I, WILMER STANLEY SNOW, a citizen of the United States of America, residing at Oak Park, in the county of Cook and State of Illinois, have invented a new, original, and ornamental Design for Lighting Fixtures, of which the following is a specification, reference being had to the accompanying drawing, forming a part thereof.

The figure is an elevational view of the lighting fixture, made according to my design.

I claim:

The ornamental design for a lighting fixture, as shown.

WILMER STANLEY SNOW.
